UNITED STATES PATENT OFFICE.

JAMES C. KIMSEY, OF PHILADELPHIA, PENNSYLVANIA.

WARDROBE BATH-CABINET.

No. 904,488.

Specification of Letters Patent.

Patented Nov. 17, 1908.

Application filed June 25, 1906. Serial No. 323,317.

To all whom it may concern:

Be it known that I, JAMES C. KIMSEY, a citizen of the United States, residing in Philadelphia, Pennsylvania, have invented 5 certain Improvements in Wardrobe Bath-Cabinets, of which the following is a specification.

The object of my invention is to make a combined wardrobe and bath cabinet which 10 will take up very little space and in which the bath tub is entirely hidden from view.

The invention is particularly adapted for use in apartments having limited space.

In the accompanying drawings: Figure 1, 15 is a front view of my improved wardrobe and bath cabinet; Fig. 2, is a longitudinal section on the line 2—2, Fig. 3; Fig. 3, is a sectional plan view on the line 3—3, Fig. 2; Fig. 4, is a transverse sectional view on the line 4—4, Fig. 2; Fig. 5, is a perspective view of the bath tub detached; Fig. 6, is a 20 sectional view on the line 6—6, Fig. 5, drawn to a smaller scale; and Fig. 7, is a sectional view on the line 7—7, Fig. 5, drawn to a 25 smaller scale.

In outside appearance the cabinet is similar to the ordinary double wardrobe found in modern houses.

A is the frame of the structure consisting 30 of side members $a-a$ and a back a' .

a^2 is the floor and a^3 is the top of the cabinet.

B and B' are the doors of the cabinet; the doors being hung from a stile A' forming 35 part of the fixed frame of the structure. In the doors are mirrors $b-b'$ and by swinging the doors at an angle one to another, as illustrated in Fig. 3, the person standing between the two mirrors can use both.

40 The structure is divided into two compartments D and C by a partition A². In the bottom of the compartment D is a bath tub E. This tub is of such a length that it extends beyond the line of the main portion of 45 the partition A² and this partition is set back so as to allow sufficient room for the placing of the tub, as illustrated in Fig. 2, leaving a portion of the compartment C to be utilized as desired. This portion of the compartment 50 may be used as a wardrobe, the clothes being hung full length. In the compartment C are shelves.

The tub E is preferably formed as shown in Fig. 5, having a flange throughout its entire upper edge, the flange being turned down at e opposite the door B', while the

rest of the flange is turned up, as at e', so that it can be readily secured to the metal lining d of the compartment D by screws d', 60 bolts, or other fastenings.

By flanging the tub, as shown in Figs. 5, 6 and 7, I provide a shelf for the slide F, which carries a wash bowl f, so that the slide can be moved into and out of position, as desired. The slide has an upward flange f² 65 which extends under a flange of a rail d' secured to the back of the structure, as indicated in Fig. 2.

G is the water supply pipe, which may be 70 the city supply or may come from a reservoir at the top of the cabinet, as desired. The spigot g is in such position that the water will flow directly into the basin when it is placed in the position illustrated in Fig. 2, or, if the basin is moved back, the water will 75 flow into the tub. The tub, as is usual, has an outlet H and an overflow h.

In some instances I may provide a water heater I having a coil i connected to the water pipe G and a three-way valve g' may 80 be used at the point indicated in Fig. 4, so that the water may flow direct or through the water heater.

i' is a vent leading from the water heater out at the top of the cabinet. The opening 85 for the passage of this vent pipe is larger than is necessary so as to allow free vent for the cabinet itself.

D' is a closet above the compartment D and this closet is provided with a door in 90 addition to the main door B', although this extra door is not necessary in some instances.

D² is a space under the corner of the tub closed by a hinged door B² and this space 95 can be used for boots and shoes, if desired. On the opposite side is a door b³ and on opening the door B and the door B³ the entire depth of the wardrobe compartment C is exposed. Thus it will be seen that my improved cabinet is compact and, when the 100 doors are closed, the tub is entirely hidden from view and the structure has the appearance of an ordinary wardrobe.

The cabinet is undercut at m so that a person using the wash basin can readily 105 reach it and the undercut m' is made to correspond with the undercut m.

I claim as my invention:—

1. The combination, in a combined bath cabinet and wardrobe, of a body portion, a 110 partition dividing the body portion into two compartments, doors for said compartments,

and a fixed bath tub horizontally disposed in the lower portion of one compartment, said tub having an outwardly disposed flange at its upper edge for the reception of securing means, and the portion of the flange opposite the door being turned down and rounded.

2. The combination of a body portion, a partition separating the body portion into two compartments, said partition having two vertical sections united by a horizontal section and increasing the width of the lower portion of one of the compartments, a bath tub mounted in a fixed position in this extended portion of the compartment, the space above the tub being unobstructed, a flange on the tub some distance below the horizontal portion of the partition, a slide mounted on the flange, a basin carried by the slide, the slide being so situated that it can be moved with the basin under the horizontal portion of the partition, a spigot so ar-

25 ranged that when the slide and the basin are moved from under the horizontal portion of the partition water can flow from the spigot into the basin.

3. The combination, in a combined wardrobe and bath cabinet, of a partition forming two compartments, a bath tub in one compartment, said bath tub having a flange on each side, a slide mounted on the flange and having an upturned edge, with a bar having a downwardly extending flange overlapping the edge of the slide, and a water inlet and outlet.

25 In testimony whereof, I have signed my name to this specification, in the presence of two subscribing witnesses.

JAMES C. KIMSEY.
